KNITTED FABRIC OR GARMENT AND IN
THE PRODUCTION THEREOF

Thomas Henry Jones, Woodthorpe, and Robert Kirkland Mills, Sherwood, England, assignors to Hosiery Developments Limited, Nottingham, England

Application July 17, 1936, Serial No. 91,180
In Great Britain July 20, 1935

10 Claims. (CL. 66—169)

This invention comprises improvements in knitted fabrics or garments and in the production thereof and has particular, although not exclusive, reference to ladies' stockings made of fine gauge fabric.

An important object of the present invention is to eliminate or minimize the possibility of the quality or appearance of knitted fabric, articles or garments being impaired by the production 10 therein of undesirable lines due to inequalities or variations in the size and/or shade of the yarn employed in knitting the articles; said lines, in the case of ladies' full-fashioned fine gauge silk stockings made on a Cotton's patent or like 15 straight bar machine, usually appearing in the form of rings.

It has heretofore been proposed, with the object of minimizing this defect in the production of stockings on a straight bar machine, to knit 20 a succession of groups of stitch courses of which each group is composed of successive courses each knit from a different thread, i. e. a thread drawn from a separate supply; and in this way thread mixing is effected, that is to say threads of the 25 same colour and character taken from different supplies, and no two successive courses are knit from the same thread at that part of the stocking where the mixing is effected.

The fabric or articles in this invention has 30 incorporated therein stitches that are locked or tied by the introduction of stitch-locking thread additional to the stitch-forming thread, thereby eliminating or reducing the possibility of stitch-laddering or running; and according to the present invention a knitted fabric or article of this 35 kind produced on a straight bar knitting machine is provided composed of two or more threads and in which different threads, (threads drawn from different supplies) functioning either as ground 40 thread (stitch thread) and/or stitch-locking thread, are laid in successive knitted courses. In this way a ladderproof or ladder-resistant knitted fabric knitted on a straight bar machine is provided wherein different threads appear in 45 successively knitted courses as ground threads and/or as stitch-locking threads, and the threads in the fabric are thereby effectively mixed so as to eliminate or minimize irregularities in the finished fabric as aforesaid.

50 The particular construction of the fabric can be varied in many ways within the ambit of the present invention. For example, the fabric or article may be composed of two or more threads and each thread of at least two threads may

function as a ground thread on some courses and as a stitch-locking thread on other courses.

The improved knitted fabric or garment may be of the kind which is rendered ladderproof or ladder-resistant by the incorporation of 5 stitches that are locked or tied by the introduction of stitch-locking thread additional to the stitch-forming thread. Advantageously, although not necessarily, locking or tying of the stitch loops is effected by passing a thread loop 10 through and also around or over another loop, or, in other words, by completely encircling each side bar or leg of a stitch loop with locking thread which also extends from one side to the other of said loop.

15 For the purpose of more fully describing the nature of this invention reference will now be made to the accompanying drawings, wherein:—

Figs. 1 to 6 illustrate six embodiments of improved fabric according to the present invention. 20

In every case the fabric is composed of two different or distinct threads, i. e. threads of the same kind and shade drawn from different supplies. In the construction shown in Fig. 1 four threads drawn from different supplies are incorporated, three of said threads *a*, *b* and *c* being employed as ground or stitch-forming threads, hereinafter referred to as ground threads, and the fourth thread *d* being employed as a stitch-locking thread. Stitch courses are 30 formed in succession from the three ground threads *a*, *b* and *c* and the stitches in each course are locked by one and the same stitch-locking thread *d*.

35 In producing this fabric on a Cotton's patent or similar straight bar knitting machine, such as is employed in the production of full-fashioned stockings, four thread carriers or guides operate over each section of the machine, each carrier receiving thread from a separate supply, and all the threads being advantageously of the same kind in every respect. Three of the carriers operate to lay the three ground threads *a*, *b* and *c*, while the fourth carrier operates to traverse the stitch-locking thread *d*. One carrier supplied 40 with the thread *a* is first traversed across the needles which are then operated to produce the first course 1 of knitted stitches in the customary manner, said carrier being retained at the end of its traverse. The carrier supplied with the 45 locking thread *d* is then traversed to lay its thread and the needles are operated to produce therefrom locking loops about the ground thread stitches in course 1. The carrier supplied with the second ground thread *b* is then traversed to 50

55

make a second course 2 of stitch loops interlinking with the stitch loops in course 1, and the carrier appertaining to this ground thread *b* is retained at the end of its traverse. The carrier supplied with the locking thread *d* is then traversed back across the needles in an opposite direction to lock the stitch loops in course 2, after which the ground thread carrier supplied with the thread *c* is then traversed to form a third course 10 3 of ground thread loops interlinking in the customary manner with the stitches of the last produced course 2, and the carrier supplied with the locking thread *d* is then again traversed in a reverse direction to lock the stitch loops in said 15 third course 3. After this the before-described movements are repeated by first traversing the ground thread carrier supplied with the thread *a* to produce course 4 of stitches which are then locked by traversing the carrier supplied with the 20 locking thread *d*, this being followed by the traverse of the carriers to lay the ground threads *b* and *c*; it being understood that after each course of stitches has been produced the locking thread *d* is traversed to lock said stitches.

25 In the construction shown in Fig. 2 six thread carriers are employed, three of said carriers functioning to lay three different ground threads, *e*, *f* and *g*, and the remaining three carriers functioning to lay three different locking threads 30 *h*, *i* and *j*. The production of this fabric shown in Fig. 2 is similar to that described with reference to Fig. 1 except that instead of laying the same locking thread at each successive course, the three distinct locking threads *h*, *i* and *j* are separately and sequentially laid at successive stitch courses; consequently each group of three successive stitch courses is composed of three distinct ground threads and three distinct stitch-locking threads, the order of laying the several 35 threads in the production of courses 1, 2 and 3 being repeated in courses 4, 5 and 6 and to any desired extent throughout the fabric.

The construction shown in Fig. 3 is the reverse of that shown in Fig. 1, that is to say whereas 45 in Fig. 1 three distinct ground threads *a*, *b* and *c* are employed and selectively laid to form successive stitch courses, each course being locked by one and the same stitch-locking thread *d*, in Fig. 3 one and the same ground thread *k* is 50 traversed by one and the same carrier to and fro to produce successive courses of stitches, while three carriers supplied with three distinct stitch-locking threads *l*, *m* and *n* are operated in succession to traverse their threads and lock the 55 stitches in successive courses.

Figs. 4 and 5 illustrate examples of fabric composed of two or more different or distinct threads in which each thread of at least two threads functions as a ground thread on some courses and 60 as a stitch-locking thread on other courses or vice versa. In the construction shown in Fig. 4, two threads *o*, *p* are employed, each thread functioning at one stitch course as a ground thread and at the next succeeding course as a stitch-locking thread, the thread change being, therefore, effected at successive courses. In other words, each of the two threads *o*, *p* is laid on alternate courses as a stitch-forming thread and on the remaining alternate courses as a stitch-locking thread, the alternate traverse of the two 65 thread carriers being continued throughout the fabric.

In the modification shown in Fig. 5 four threads *q*, *r*, *s* and *w* are employed, said threads being laid 70 in succession to produce successive stitch

courses, and each thread being subsequently traversed in an opposite direction as a locking thread to lock the stitches in a subsequently knitted course. In this case, however, instead of returning a thread laid as a ground thread in one course to lock the stitches formed from another ground thread in the next succeeding course, each thread is returned to lock the stitches in the next but one succeeding course. In other words, assuming that courses 1, 2 and 3 10 of ground thread stitch loops are produced respectively from threads *q*, *r* and *s*, the thread *q* forming course 1 is subsequently traversed in a reverse direction to lock the stitches in course 3, whilst the thread *r* forming course 2 is returned 15 to lock the stitches in course 4, and the thread *s* forming course 3 is returned to lock the stitches of course 5, and so on throughout the fabric.

In the further modification illustrated in Fig. 6 three distinct threads *t*, *u*, *v* are employed. In 20 this construction, however, each thread is first laid in one direction to produce a course of ground thread loops and is immediately returned in an opposite direction to constitute a locking thread and lock the stitches formed from the 25 same thread. When course 1 has been produced from the thread *t*, said thread is returned as a locking thread to lock the stitches in said course. The second thread *u* is now traversed to form course 2 of stitch loops interlinking with the loops 30 of course 1 and said second thread *u* is immediately returned to lock the stitches in this course. The third thread *v* is now traversed to form a third course of interlinking stitches, said thread *v* being also returned to lock the stitches in said 35 third course. The thread *t* appertaining to course 1 is now again traversed to form course 4 and return in an opposite direction to lock the 40 stitches of such course, after which the thread *u* appertaining to course 2 is again traversed to form course 5 and return to lock the stitches of said course, the third thread *v* being then traversed to form course 6 and return to lock the 45 stitches therein, this being repeated throughout the fabric. It will, of course, be appreciated that the number of threads successively laid to produce ground thread stitches and to lock said 50 stitches may be varied as desired. For example, only two such threads may be employed and traversed alternately.

In fabrics according to the present invention where a plurality of different or distinct ground threads are employed and the locking thread or threads is or are retained throughout the fabric as a locking thread or threads, the latter may be 55 appreciably finer than said ground threads and consequently less conspicuous in the finished fabric. In such case, however, it must be borne in mind that different ground threads are laid at successive courses.

From the above it will be appreciated that in any two consecutive courses of stitches different threads are employed either as ground threads or locking threads or both, consequently the thread change from one course to another effectively eliminates or minimizes striping or ring effects in a knitted fabric or article such as a stocking. The number of different threads, i. e. threads withdrawn from different supplies introduced in the fabric can be varied as desired within the ambit of the present invention, and in the production of certain classes of garments or articles the traverse of the locking thread may be interrupted to suit existing requirements.

We claim:—

1. A flat knitted fabric or article composed of a plurality of threads drawn from different supplies in which each thread of at least two threads functions as a ground thread and also 5 as a stitch-locking thread on the same course and wherein successive courses of stitches are formed from different threads, i. e. threads withdrawn from different supplies.
2. A flat knitted fabric or article composed of 10 two different threads, i. e. threads drawn from different supplies, wherein at each course one of said threads is laid as a ground or stitch-forming thread and the other thread is laid as a stitch-locking thread and wherein the thread 15 functioning as a ground thread in one course constitutes a stitch-locking thread in the next succeeding course and vice versa.
3. A flat knitted fabric or article composed of a plurality of threads drawn from different 20 supplies wherein at least two different threads function as ground threads and at least another two different threads function as stitch-locking threads and wherein both the ground threads and the stitch-locking threads are changed at 25 successive stitch courses.
4. A flat knitted fabric embodying stitches that are locked or tied by stitch-locking thread to minimize or obstruct stitch-laddering or running, said fabric being composed of a plurality 30 of different threads (threads drawn from different supplies), each of a succession of knitted courses comprising ground thread (stitch thread) and stitch-locking thread and no two successively knitted courses of said succession of courses 35 having therein identical threads embodied and functioning in the same manner in each course.
5. A flat knitted fabric embodying stitches that are locked or tied by stitch-locking thread to minimize or obstruct stitch-laddering or running, said fabric being composed of a plurality of 40 different threads (threads drawn from different supplies), each of a succession of knitted courses comprising ground thread (stitch thread) and stitch-locking thread and different threads appearing in successively knitted courses of stitches 45 as ground threads, (stitch-forming threads).
6. A flat knitted fabric embodying stitches that are locked or tied by stitch-locking thread to minimize or obstruct stitch-laddering or running, said fabric being composed of a plurality of different threads (threads drawn from different supplies), each of a succession of knitted courses comprising ground thread (stitch thread) and stitch-locking thread and different threads appearing in successively knitted courses of stitches as ground threads. (stitch-locking threads).
7. A flat knitted fabric embodying stitches that are locked or tied by stitch-locking thread to minimize or obstruct stitch-laddering or running, said fabric being composed of a plurality of different threads (threads drawn from different supplies), each of a succession of knitted courses comprising ground thread (stitch thread) and stitch-locking thread and different threads appearing in successively knitted courses of stitches both as ground threads and as stitch-locking threads.
8. A flat knitted fabric embodying stitches 20 that are locked or tied by stitch-locking thread to minimize or obstruct stitch-laddering or running, said fabric being composed of a plurality of different threads (threads drawn from different supplies), each of a succession of knitted 25 courses comprising ground thread (stitch thread) and stitch-locking thread and each thread of at least two different threads functioning both as a ground thread and as a stitch-locking thread.
9. A flat knitted fabric or article composed of more than two threads drawn from different supplies, said threads being employed in succession to form successive courses of stitches, and said threads being also employed in succession 30 to lock the stitch loops formed from the same thread.
10. The production of a knitted fabric or article from three different threads, i. e. threads drawn from different supplies, said threads being 40 employed in succession to produce successive courses of stitches and each thread after being traversed and laid in one direction to produce a course of stitch loops being immediately traversed in an opposite direction to lock the stitch 45 loops thus formed.

THOMAS HENRY JONES.
ROBERT KIRKLAND MILLS.
